Primary Examiner — Kevin K Rudzinski*Assistant Examiner* — Richard Kearney(74) *Attorney, Agent, or Firm* — Lippincott IP, LLC; Patricia P. Werschulz, Esq.(57) **CLAIM**

The ornamental design for a cast paper flower sconce, as shown and described.

DESCRIPTION

FIG. 1 is a perspective view of a cast paper flower sconce, showing our new design;

FIG. 2 is a bottom plan view thereof;

FIG. 3 is a top plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The broken lines shown in the drawings illustrate portions of the cast paper flower sconce that form no part of the claimed design.
